UNITED STATES PATENT OFFICE.

HERMAN LEINWEBER, OF CHICAGO, ILLINOIS.

AIRSHIP.

1,108,865.

Specification of Letters Patent. Patented Aug. 25, 1914.

Application filed February 1, 1913. Serial No. 745,564.

To all whom it may concern:

Be it known that I, HERMAN LEINWEBER, a citizen of the United States, and a resident of the city of Chicago, county of Cook, and 5 State of Illinois, have invented certain new and useful Improvements in Airships, of which the following is a specification.

My invention relates to an improvement in air ships and especially to supporting 10 planes therefor, and has for its object, the provision of a plane for air ships of improved construction and operation and especially designed to assist in elevating the ship and in steadyng the motion of the ship 15 on an even keel.

The invention consists in the combinations and arrangements of parts hereinafter described and claimed.

The invention will be best understood by 20 reference to the accompanying drawings forming a part of this specification, and in which,

Figure 1 is a side elevation of an air ship equipped with a plane embodying my invention, Fig. 2, an end view of the same, and 25 Fig. 3, a longitudinal central section taken through the plane.

The preferred form of construction, as 30 illustrated in the drawings comprises a supporting plane 1 which is formed of a frame 2 of any suitable construction and covered by canvas or other suitable material, as will be readily understood by those skilled in the art. This plane is formed with its longitudinal 35 sides or edges depressed and downwardly curved throughout the main or body portion thereof, thus forming a plane of concavo-convex shape in cross section transversely of its length. At each end the corners 40 of the plane 1 are upwardly inclined until they attain the same level as the central portions thereof, so that each extreme end of the plane is flat and level as shown in Fig. 2. By this arrangement of the ends of 45 the planes the lifting action thereof, when forced through the air in either direction is augmented, and the travel of the ship on an even keel facilitated.

A suitable car 4 is suspended from the 50 plane on suitable hangers 5 and suitable propellers 6 are arranged in a suitable frame 7 which is in turn braced and supported from car 4 and from plane 1 by means of hangers or braces 8. Suitable power devel-

oping means is arranged in car 4 and suitable connections are made with propellers 5 for driving the latter. Suitable rudders 9 are also provided for steering the ship in either direction and suitable connections are made for operating these rudders. The 60 means for driving and controlling the ship constitute the subject matter of my Patent No. 1,064,232, granted June 10, 1913, and need no further description here.

While I have illustrated and described the 65 preferred form of construction for carrying my invention into effect, this is capable of variation and modification without departing from the spirit of the invention. I, therefore, do not wish to be limited to the 70 precise details of construction set forth, but desire to avail myself of such variations and modifications as come within the scope of the appended claims.

Having described my invention what I 75 claim as new and desire to secure by Letters Patent is:

1. An air ship plane concavo-convex in form in its main portion with its longitudinal sides depressed and having its forward 80 corners upwardly and longitudinally inclined, substantially as described.

2. An air ship plane concavo-convex in form in its main portion with its longitudinal sides depressed and having its corners 85 upwardly and longitudinally inclined, substantially as described.

3. An air ship plane concavo-convex in form in its main portion with its longitudinal sides depressed and having its forward 90 corners upwardly and longitudinally inclined to the same level as the corresponding central portion thereof, substantially as described.

4. An air ship plane concavo-convex in 95 form in its main portion with its longitudinal sides depressed and having its corners upwardly and longitudinally inclined to the same level as the corresponding central portion thereof, substantially as described. 100

In testimony whereof I have signed my name to this specification in the presence of two subscribing witnesses.

HERMAN LEINWEBER.
